(57) CLAIM

I claim the ornamental design for a handbag with a stitching pattern, as shown and described.

DESCRIPTION

FIG. 1 is a perspective view of a handbag with a stitching pattern, according to the new design.

FIG. 2 is a front view of the handbag with a stitching pattern, according to the new design.

FIG. 3 is a rear view of the handbag with a stitching pattern, according to the new design.

FIG. 4 is a right side view of the handbag with a stitching pattern, according to the new design.

FIG. 5 is a left side view of the handbag with a stitching pattern, according to the new design.

FIG. 6 is a top view of the handbag with a stitching pattern, according to the new design; and,

FIG. 7 a view of the handbag from the bottom, where the stitching pattern is not visible.

The wider broken lines showing the body of the handbag are for the purposes of illustrating environment and form no part of the claimed design.
